UNITED STATES PATENT OFFICE.

ARTHUR L. STRAHLER, OF BENSON, NEBRASKA, ASSIGNOR OF ONE-HALF TO LEONIDAS P. BYARS, OF BENSON, NEBRASKA.

COMBINED TIMER AND DISTRIBUTER.

1,156,255.

Specification of Letters Patent.

Patented Oct. 12, 1915.

Application filed March 4, 1914. Serial No. 822,304.

To all whom it may concern:

Be it known that I, ARTHUR L. STRAHLER, a citizen of the United States, residing in Benson, in Douglas county, in the State of 5 Nebraska, have invented certain new and useful Improvements in Combined Timers and Distributers, and have described the same in the following specification, illustrated by the accompanying drawings.

10 My invention relates to that class of combined timers and distributers which are commonly used with the internal combustion engines of automobiles and the like, and which individually comprise an induction 15 coil, a timer connected with the primary circuit of that coil, and a distributer for directing the secondary current to the spark plugs severally.

It is the object of the invention, to give 20 to the normally separated contacts of the timer a mutually rubbing movement while in contact; to move those contacts to a distance from each other through the action of the timer shaft whenever the normal direction of rotation of that shaft is reversed; and in general to increase the efficiency of 25 combined timers and distributers of the specified class. To accomplish this object I incorporate in my improved apparatus a 30 pivoted slide of special construction, actuating one of the timer contacts and actuated conjointly by a spring and by a cam which is carried by the timer shaft.

In said drawings, illustrating the best 35 manner in which I have contemplated applying to a four-cycle engine the principles of my invention, Figure 1 is an axial section of a combined distributer and spark timer, constructed in accordance with these 40 principles and mounted in a supporting bracket. Fig. 2 is a cross section of the same on the line 2—2 of Fig. 1, showing the timer contacts as normally separated. Fig. 3 is a side elevation of the same, mounted in 45 operative position on the crank-case of the engine. Fig. 4 is a transverse sectional view on the line 4—4 of Fig. 1, and shows the contacts of the timer as separated widely by the reversal of the time shaft. Fig. 5 is a 50 detail, being an end elevation of the pivoted slide, with a contact-carrying spring thereon. Fig. 6 is a detail, being an enlarged plan of the same slide and other parts of the timer, showing its contacts rubbing.

55 This illustrative and illustrated speci-

men of my invention is shown mounted upon the crank-case 36 of an engine having the crank-shaft 37 and four cylinders 38. The timer shaft 1 occupies an approximately vertical position in the bracket 2 on the 60 crank-case, and is actuated from the cam shaft 3 by the intermeshing beveled gears 4 and 5. This timer shaft is journaled in the sleeve 6 which is seated in a rotarily adjustable manner in the boss 7 of this bracket. 65 This sleeve has a broad horizontal flange 8, resting on the top of the boss 7 and forming the annular bottom plate of the closed casting, or contact box, 9. By means of the advance rod 39 and the lug 9' on the underside of this plate, the latter is rotarily adjustable for the purpose of controlling the advance and retardation of the spark in the usual manner. On the flat and smoothed area, or facet, 10, of this plate, is 70 positioned horizontally the pivoted slide 11, which is of the nucleus of the invention. It comprises in this instance a rectangular hollow head 11', a vertical longitudinal slot 12 perforating the head, a straight shank 13 75 extending from one end of the head in the direction of the length of the slot, a horizontal arm 14 extending laterally from the other end of the head, and an engagement shoulder 15 formed in one margin of the 80 slide. It is attached to the plate 8 in sliding contact with the area 10 by the screw-pointed pivot pin 16, which, projecting from that area, and through the slot 12, permits the slide to move thereon both rotarily and 85 endwise. The arm 14 of this slide has a straight horizontal conductive and elastic extension, or spring, 17, carrying on its free end the contact point 18, within reach 90 of the fixed contact point 19, which is adjustably mounted upon the bottom plate 8 by means of the insulated plate 20. By the tension spring 21, which connects the lug 22 with this slide, the latter is constantly pulled 95 both slidily lengthwise in a direction to bring the contacts 18 and 19 together and also rotarily toward or against the adjacent guiding lug 23.

To the timer shaft, and immediately above the plate 8, is keyed the ratchet-like snap cam 24, which is a tappet wheel having a plurality of vertical equidistant peripheral facets 25, equal in number to the cylinders of the engine. These facets normally contact successively with that side of the slide 100 105 110

11 which is next to the lug 23; and are kept lubricated by making successive contacts with the circular oil-carrying brush 26, which is formed of felt or other porous material and is rotarily mounted on the pivot pin 26' in position to be rubbed and rotated by those contacts.

5 The distributor comprises the insulated and radially positioned contact strip 27, 10 which is mounted on the top of the timer shaft, contacting constantly with the central contact point 28, and successively with the four peripheral and equidistant contact points 29, all these points being arranged in 15 customary correlative positions in the top of the box 9.

10 The cylindrical hood, or cap 30, formed of insulating material, and forming the top and the peripheral wall of the box 9, is 20 fitted to the margin of the plate 8, and is secured thereon in the position shown, by means of the screws 35 in the screw-holes 31; while the contact point 28 and the several contact points 29 in the top of the box 25 are connected into the secondary circuit of the induction coil by the several insulated cables 32 and 32' respectively. These cables are led in through the top of the box and through the projecting and close-fitting 30 nipples 33 thereof, and are severally wedged into these nipples respectively by the tapering points of the conductive screws 34; these screws being provided with or comprising the contact points last mentioned. 35 By this construction all the contact points are inclosed in the box; and the cables, being continuously insulated from end to end, are efficiently protected from dirt and dampness.

40 The electrical connections of the apparatus, which are not fully indicated in the drawings, are to be understood to be such as to bring the contacts 18 and 19 into the primary circuit of the induction coil, and 45 the contacts 28 and 29 into the secondary circuit, for the purpose of opening and closing those circuits simultaneously in the usual manner during the normal running of the engine.

50 In the operation of the invention, the slide 11, whenever engaged by any one of the facets of the cam 24 rotating in its normal direction, is thereby turned rotarily on its pivot pin 16 from the position shown in 55 Fig. 2 and from contact with the lug 23, through the position shown in full lines in Fig. 6 to that shown in broken lines. By this pivotal movement of the slide, and by the accompanying movement of its elastic 60 arm extension 17, the contact points 18 and 19 are first brought into abutting contact with each other, and then rubbed contactingly together, as indicated in the figure last mentioned. Then, as the cam continues 65 its rotation, and the same cam facet ceases

to engage the slide, the latter is returned by the spring 21 to the normal position of contact with the lug 23, which position is shown in Fig. 2. By this return movement of the slide and by the accompanying retractile 70 movement of its flexible arm extension 17, the same contact points are first rubbed together in a reverse direction, and are then separated to the positions shown in that figure. But whenever the slide is engaged by 75 the cam rotating in the reverse direction, it is thereby pushed endwise by the shoulder 15, in sliding contact with the lug 23, and against the resistance of the spring 21, to the position shown in Fig. 4. By this sliding movement it separates the primary contacts to such a distance as to preclude the 80 passage of current between them, and thereby prevents the engine from running backward.

85 I claim as my invention—

1. A combined timer and distributor of the specified class, comprising a pair of contacts in the primary circuit, contacts in the secondary circuit, and means operated by the timer shaft for rubbing said pair of points back and forth against each other, and for producing successive contacts in the secondary circuit. 90

2. A combined timer and distributor of 95 the specified class, comprising a pivoted slide carrying one of the contact points of the primary circuit, a rotating timer cam actuating the slide, and a lubricating brush contacting with the cam. 100

3. A combined timer and distributor of the specified class, comprising a timer shaft, a distributor located in the secondary circuit of the induction coil and operated by the timer shaft, a pair of contact points for 105 opening and closing the primary circuit, a pivoted slide, movable both longitudinally and rotarily, a spring arm outstretched from the slide, a pair of contact points in the primary circuit, one of these points being stationary and the other being carried by the arm, a spring actuating the slide longitudinally to bring the points into juxtaposition without contact, and a cam keyed on the timer shaft, and intermittently turning the 110 slide pivotally in a direction to rub the contact points together. 115

4. A combined timer and distributor of the specified class, comprising a timer shaft, a cam thereon, a distributor connected with the secondary circuit and operated by the timer shaft, a pivoted slide movable both longitudinally and pivotally by the cam, and a pair of contact points in the primary circuit, which are separated and approximated by the longitudinal movements of the slide and are rubbed together by its pivotal movements. 120

5. A combined timer and distributor of the specified class, comprising a timer shaft, 125

- a distributor operated thereby in the secondary circuit, a cam on the shaft, a slide operated both pivotally and longitudinally by the cam, a spring arm projecting laterally from the slide, and a pair of contact points in the primary circuit, one of these points being stationary and the other being carried by the free end of the arm; whereby the longitudinal movements of the slide separate and approximate the contact points, and the pivotal movement of the same rubs the points together. 5
6. A combined timer and distributor of the specified class, comprising a pivoted slide carrying one of the contact points of the primary circuit, a rotating timer cam actuating the slide, and a lubricating rotatable brush contacting with the cam. 10
7. In a combined timer and distributor of the specified class, a contact box comprising an annular base for the accommodation of the timer shaft, and a cylindrical cap of insulating material thereon, having a plurality of upwardly projecting hollow nips. 15
8. A combined timer and distributor of the specified class, comprising a pair of contact points in the primary circuit, contact points in the secondary circuit, means operated by the timer shaft for producing contacts in the secondary circuit, and similarly operated means for rubbing the contact points in the primary circuit together reciprocatingly. 20
- In testimony whereof I subscribe this specification in the presence of two witnesses.
